UNITED STATES PATENT OFFICE.

FERDINAND A. HOYA, OF MILWAUKEE, WISCONSIN, ASSIGNOR OF ONE-HALF TO WILLIAM WOODS PLANKINTON, OF MILWAUKEE, WISCONSIN.

SAD-IRON.

No. 849,381.

Specification of Letters Patent.

Patented April 2, 1907.

Application filed April 3, 1905. Serial No. 253,526.

To all whom it may concern:

Be it known that I, FERDINAND A. HOYA, a citizen of the United States, residing at Milwaukee, county of Milwaukee, and State of Wisconsin, have invented new and useful Improvements in Sad-Irons, of which the following is a specification.

My invention relates to improvements in sad-irons, and pertains especially to that class of sad-irons which are heated by gasolene, a supply of which is stored in a suitable reservoir connected with the sad-iron.

The object of this invention is to provide a form of sad-iron of the described class in which the reservoir will be suitably heated, but not overheated, and will be located in such a position that it will not burn the hands of the operator. Also to provide means for conveying the gasolene to the burner along a highly-heated zone, in connection with means for preventing the oil-duct from becoming clogged.

A further object of my invention is to provide a form of construction in which the air and hydrocarbon gas will be mixed in a separate chamber within the body of the iron and a sufficiently-perfect mixture secured to insure complete combustion.

In the following description reference is had to the accompanying drawings, in which—

Figure 1 is a plan view of the body of a sad-iron embodying my invention with the cap-plate and handle removed. Fig. 2 is a central vertical longitudinal sectional view of a sad-iron embodying my invention. Fig. 3 is a central cross-sectional view of the same. Fig. 4 is a side view with the cap-plate raised.

Like parts are identified by the same reference characters throughout the several views. The body of my improved sad-iron comprises a base portion 1, the upper margins of the side walls of the base being recessed at 2. The base is provided with an interior cavity partially subdivided by partition-flanges 3 into two compartments. The forward compartment communicates with the exterior through apertures 4 in the side walls. The rear compartment constitutes the combustion-chamber and is provided with a series of vertical heat-absorbing flanges 5, which project inwardly from the side walls. The rear end wall of the base portion is cut out, as indicated at 6.

A cap-plate 7 is hinged to the body at 8 and is provided with a suitable handle 9, which is connected with the plate by means of arms 10, the head-piece 11, and the forked standards 12. A storage-tank 13 for gasolene or other combustible fluid is mounted between the standards 12, and a deflecting-plate 14, also mounted between the standards, is interposed between the tank and the cap-plate 7, with an air-space above and below the plate. A feed-tube 15 leads downwardly from the tank 13 through the cap-plate 7 and communicates with a heating-tube 16, extending horizontally underneath the cap-plate and supported therefrom. The front end of the tube 16 is provided with a valve-nut 17, in which a valve-rod 18 has screw-threaded engagement, the end of the rod being faced off at 19 to form a valve provided with a needle 20, extending through a small aperture in the nut 17. The valve 18 projects outwardly through a suitable packing at the rear end of the tube 16 and is provided with a hand-wheel 21 for opening and closing the valve. A burner-tube 22 is located underneath the tube 16 and is provided with slits 23 in its under surface, as in any ordinary burner-tube of this character. The front end of the burner-tube is provided with a reverse bend at 24, terminating opposite the valve-nut 17 and adapted to receive gas escaping through the aperture in said nut 17 past the needle 20, this gas being thoroughly mixed with air in traversing the open space between the nut and the opposing end of the burner 22.

The tube 16 is provided with a downwardly-projecting heat-absorbing flange 25, which extends into comparatively close proximity to the burner-tube and absorbs heat therefrom to heat the combustible fluid in the tube 16. Heat-deflecting shields 26 are provided on each side of the tube 16 and are supported from the latter by arms 27. These shields are preferably formed in one piece, which is bent over the tube 16. They are covered with an asbestos lining 28 and protect the cap-plate to a considerable extent from the heat of the burner. These shields 26 are formed to cover the recesses between the heat-absorbing flanges 5, but are not in actual contact with said flanges, a sufficient space being left to permit free circulation.

When the cap-plate is in position for use, the bracket 30, which supports the heating-tube 16 and burner-tube 22, substantially fills the space between the partition-flanges 3. A shield 31, connected with the rear end portions of the shields 26, extends downwardly in a position to fill the recessed or cut-away portion of the rear end wall 6. When the cap-plate is in a raised position, this shield 31 swings inwardly, and the hand-wheel 21 swings into the recessed portion of the rear end wall. The cap-plate extends to the rear a sufficient distance to abut the rear ends of the side walls, and thus holds the plate in a vertical position when the iron is opened, as shown in Fig. 4. When closed, the front end of the plate is secured by means of a swinging latch 32, pivotally connected with the base 1 and having a thumb-nut 33, adapted to engage the front end of the cap-plate, the cap-plate being recessed for the reception of the latch-pin.

Having thus described my invention, what I claim as new, and desire to secure by Letters Patent, is—

1. In a sad-iron of the described class, the combination with a body, of a cap-plate hinged thereto at one end; a set of forked standards on the cap-plate; a tank mounted between said standards above the cap-plate; a handle having supporting-arms connected with the standards; a burner located below and supported from the cap-plate; and deflecting-plates above and below, and connected with, the cap-plate, and interposed between the tank and burner, with intervening air-spaces.

2. In a sad-iron of the described class, the combination with a cap-plate having a duct for fluid fuel; a burner underneath the cap-plate; and a heat-conveying flange projecting from the walls of said duct in the direc-

tion of the burner substantially in a plane common to the duct and burner.

3. In a sad-iron of the described class, the combination of a chambered base; a cap-plate therefor hinged thereto at one end; a burner connected with the cap-plate; a bracket on the cap-plate supporting the burner; and flanges in the base, adapted to coöperate with the bracket in subdividing the chambered base into compartments; and means for mixing air and combustible fluid in one compartment and conveying it to said burner in the other compartment.

4. In a sad-iron of the described class, the combination of a chambered base, partially subdivided by interior partitions; a cap-plate hinged to the base; a burner connected with the cap-plate; a support for said burner supplementing said partitions; means for mixing air and fluid hydrocarbon at one side of said partitions and conveying the same through said support to the burner.

5. In a sad-iron of the described class, the combination of a chambered base partially subdivided by interior partitions; a cap-plate hinged to the base; a burner connected with the cap-plate; a support for said burner supplementing said partitions; means for mixing air and fluid hydrocarbon at one side of said partitions and conveying the same through said support to the burner; said cap-plate being extended and formed to abut the base below the hinges when the plate is raised, whereby the plate is supported in a raised position.

In testimony whereof I affix my signature in the presence of two witnesses.

FERDINAND A. HOYA.
